UNITED STATES PATENT OFFICE.

RICHARD HOWLAND RANGER, OF BROOKLYN, NEW YORK, ASSIGNOR TO RADIO CORPORATION OF AMERICA, A CORPORATION OF DELAWARE.

METHOD AND MEANS OF RECEIVING SIGNALS.

Application filed November 12, 1921. Serial No. 514,456.

To all whom it may concern:

Be it known that I, RICHARD HOWLAND RANGER, a citizen of the United States, residing in the borough of Brooklyn, Kings 5 County, city and State of New York, have invented certain new and useful Improvements in Methods and Means of Receiving Signals, of which the following is a specification accompanied by drawings.

10 This invention relates to methods and means of receiving signals and is more particularly useful in connection with wireless telegraphy, though it is not limited thereto.

It is well known that atmospheric disturbances commonly called "static" interfere with reception of radio telegrams as the currents generated in the receiving systems by such disturbances blend with the signal currents and render the message more or 15 less indistinct and quite frequently wholly unintelligible. There have been many attempts to overcome the effect of these disturbances and while some of these have been more or less successful, nevertheless, there 20 are times when static disturbances seriously affect the reception of radio messages.

My invention relates to the combination of several receivers all working on the same signal, but each receiver having some essentially different characteristic such as in respect to directional properties, different location, damping, type of detector, type of receiver, etc.

The messages received through the several 35 systems are either recorded separately, and later placed adjacent to each other for the operator to interpret, or they are relayed to a central station and simultaneously recorded on the same strip of paper.

40 When the messages from the plurality of systems have been recorded it will be found in nearly all cases that the static obliterating a portion of a message received at one station is entirely absent in the message received 45 at one or more of the others or else is of such character or magnitude that this portion of the message can be distinctly read.

Further particulars in regard to the improvements will be obtained from the following description, reference being had to the drawings in which:

Fig. 1 is an illustration of three stations for receiving the messages and relaying the same to a common point.

Fig. 2 is a representation of a portion of 55 the message received at three stations.

Fig. 3 is a diagrammatic illustration of another antenna system for carrying out the improved method.

Referring to Fig. 1, circuits A, B and C 60 diagrammatically represent three receiving systems preferably located at widely separated points and having directional characteristics in respect to the signal. This has been diagrammatically indicated by extending the antennae 1, 2 and 3 in the direction of signal reception. These systems are also preferably placed at unequal distances from the transmitting station and they may have different characteristics in respect to 65 damping or resonance, type of C. W. detector, etc.

The signal received at station A may be amplified by the usual radio amplifier set 4. From the amplifier set 4 the current passes 75 through relay 7, which, through attraction of armature 8 causes periodic impulses from battery 9 to pass through means 10 for actuating the mirror 11. Beams of light from source 12 are therefore reflected on to 80 sensitive strip 13 to trace the signal thereon.

The amplifiers and rectifiers 4 and 5 may be of any type such as the well known three-electrode tubes. Since these per se are not 85 my invention the detailed construction is not given. The general principle of the photographic arrangement illustrated at 10, 11, 12 and 13 is also old and well known and it is therefore illustrated diagrammatically only.

90 Since the relay 7 will be energized throughout the entire portion of a dot or a dash even at radio frequency no heterodyne or other continuous wave detecting system is necessary and therefore none has been shown. However, it will be understood that the relay 7 could also be used with the heterodyne system if desired.

The relay contact 8 will close the circuit 100 for each dot and dash and therefore the movable film 13 when developed will have line dots and dashes as indicated at A' in Fig. 2 of the drawings.

105 The receiving system B is connected to radio amplifying set 14 and then detected in any way such as by heterodyne 15 and the beats are rectified and further amplified by the audio amplifying set 16. From the set

16 the current passes through coil 17 which controls a delicate vibratory mirror, 18 similar to the one described in connection with receiving system A. The mirror 18 will therefore oscillate at the frequency of the heterodyne beat which will be an audio frequency.

The signal coming from receiving system B through the mirror arrangement 18 will 10 appear on the developed film as indicated at B' of Fig. 2.

The signal coming from the receiving system C will be recorded after amplification and detection in the manner indicated at C' 15 in Fig. 2. Further description of the receiving system C will not be necessary as the operation will be understood from the description of the other receiving systems.

The photographic arrangement has been 20 selected by way of example as a recording device and it may be constructed in accordance with the invention disclosed in the application of Charles A. Hoxie, Serial No. 228,230, filed April 13, 1918. The photographic strip after it emerges from the developing and fixing solution will appear as 25 in Fig. 2.

By referring to Fig. 2 it will be seen that 30 static interference was being received by station C throughout the greater portion of the message. Station B' was substantially free from static except at the last portion of the message while station A' was free of static, excepting two portions where false 35 signals were given.

The operator in reading this strip will 40 find complete accord between the messages B' and A' until he gets to the point 24. Here apparently dot 25 was received from station A' but the tracings of the message received from station B' show a small amount of static or other interference 26 at this point. This makes it plain to the operator that this portion of the message is not 45 a dot but a space. Consequently, the dot will be disregarded. In general, station C received a considerable amount of static up to the point 24. The signal in the main corroborates the signal from the other two stations but if it were being interpreted alone difficulty would be had in receiving the message.

From point 24 to point 27 the message 50 from station A is clear, but apparently a long dash 28 was received at this point. At this time there was so much static at station C that this portion of the message C' will not be of much assistance in interpreting the message but by referring to the message B' 55 it will be seen that the long dash 28 of message A' is really made up by a dash and a dot since station B' was not troubled by static at this time. The operator will therefore read this portion of the message from 60 B'. Throughout the remainder of the mes-

sage the signal is read by comparison of the three messages but if the operator had one record only the interpretation might be uncertain. In the foregoing way the message received from the plurality of stations can 70 be read and compared.

In all but exceptional cases it will be possible by means of my invention to correctly read messages without difficulty. It may happen that static will be received at the 75 same instant and of similar amplitude and characteristics at all the stations but such occasions will be rare.

Even if static occurs at each of the stations of equal intensity at the same instant 80 the three recorded messages can be made to differ from each other by tuning one or more of the antennae to the signal while making the other aperiodic. Furthermore, the same result may be accomplished by operating one 85 of the heterodynes at, say, 1000 frequency above the signal and the other heterodyne at a frequency below the signal, the heterodyne beat being the same in both cases. Furthermore, different static characteristics will be 90 obtained by having the heterodyne beat in one system of a different frequency from that in the other system. For example, the heterodyne beat in one receiving system may be 1000 while the beat in the other is 1500. 95 Differentiation between the effects of static at the plurality of stations may likewise be obtained by using different types of continuous wave detectors, that is, the heterodyne or beat system may be used with one antenna 100 and the synchronous detector at one or more of the others. This latter detector is described in the application of E. F. W. Alexander, No. 323,745 filed September 15, 1919. One or more of the detectors also may 105 be of the radio chopper type such as disclosed in Goldsmith Patent No. 1,087,113, February 17, 1914.

While the particular form of recorded message at each of the stations may be the 110 same, I prefer to convert the signals at one of the stations into linear dots and dashes and one or more of the others into dots and dashes made up of vibratory tracings such as is shown in Fig. 2. The invention, however, is not limited to this particular feature.

The time of travel of the signal from the several stations, even though widely separated, will be so short that in general no 120 compensating means will be required, but if necessary, the signals may be compensated in this respect by a mechanical shifting of the position of the mirrors. When these are once set for receiving signals from a 125 particular station further adjustment will not be required.

It is preferable to send all of the messages to a common station for recording simultaneously but it is entirely practicable to in- 130

dependently record the messages at the stations and then send the dots to a common point to be assembled in adjacent position.

Also, the antenna may consist of three different types located at the same or different places. In Fig. 3 such a system is indicated. The antenna 20 is shown as of the vertical type, the antenna 21 as a closed loop and the antenna 22 as a long antenna such as is described in patent to Beverage, No. 1,381,089, June 7, 1921.

While I have shown certain types of arrangements for receiving signals and transmitting them to a common point, as well as a particular type of recording apparatus, nevertheless, it will be understood that these have been given by way of example only and that other arrangements may be used for receiving and recording the messages. It will also be understood that damped signals may be received by my improved method in which case no heterodyne will be required.

Having described my invention, what I claim is:

1. The method of receiving telegraphic messages which consists in receiving the transmitted signals forming such messages at a plurality of stations, comparing the signals received, and eliminating effects received at less than all of said stations.

2. The method of receiving telegraphic messages which consists in receiving the same message at a plurality of stations comparing the indications received at each station and selecting the proper signals from the indications received at all stations.

3. The method of receiving radio messages which consists in receiving and detecting the signals comprising the said messages at a plurality of stations and comparing the signals received and detected, to determine the transmitted signal.

4. The method of receiving telegraphic messages which consists in receiving the signals comprising such messages at a plurality of stations, recording the said signals and comparing the signals thus recorded to select the transmitted signals.

5. The method of receiving radio messages which consists in receiving the transmitted signals comprising such messages in

a plurality of circuits, comparing such signals and selecting the proper signal from the signals received.

55

6. The method of receiving radio messages which consists in substantially simultaneously receiving the signals comprising such messages in a plurality of receiving circuits and comparing the signals thus received to determine the signal transmitted.

60

7. The method of receiving radio signals which consists in substantially simultaneously receiving the signals forming such messages at a plurality of receiving stations differing in one or more receptional characteristics and comparing the signals thus received to determine the signals transmitted.

65

8. The method of reception of telegraphic communication which consists in receiving the signals in a plurality of circuits differing from each other in one or more characteristics and recording said signals in adjacent position for simultaneous reading and comparison.

70

9. The method of reception of telegraphic communication which consists in receiving the signals in a plurality of circuits differing from each other in one or more characteristics, transmitting said signals to a common point and recording them in adjacent position.

75

10. The method of reception of telegraphic communication which consists in receiving the signals in a plurality of circuits with one or more different electrical characteristics in respect to the signal, transmitting the signals to a common point and recording them in adjacent position.

80

11. The method of reception of telegraphic communication which consists in receiving the signals in a plurality of widely separated antenna systems, transmitting said signals to a common point and recording them in adjacent position.

85

12. In telegraphic receiving apparatus a plurality of receiving systems having one or more different characteristics, means for transmitting messages from each of said stations to a common point and means for recording said messages in adjacent position.
